C. Collins.

Mach. for Turning Boot Legs

N° 91,606.

Patented Jun. 22, 1869.

United States Patent Office.

CORNELIOUS COLLINS, OF WARREN, INDIANA.

Letters Patent No. 91,606, dated June 22, 1869.

IMPROVED MACHINE FOR TURNING BOOT-LEGS.

The Schedule referred to in these Letters Patent and making part of the same.

To all whom it may concern:

Be it known that I, CORNELIOUS COLLINS, of Warren, in the county of Huntington, and State of Indiana, have invented a new and improved Machine for Turning Boot-Legs; and I do hereby declare that the following is a full, clear, and exact description thereof, which will enable others skilled in the art to make and use the same, reference being had to the accompanying drawing, forming part of this specification, in which—

Figure 1 represents a plan or top view of my improved machine for turning boot-legs.

Figure 2 is a vertical longitudinal section of the same.

Similar letters of reference indicate corresponding parts.

This invention relates to a new machine for turning boot-legs after they are sewed, to prepare them for the last, its object being to facilitate the turning-process, so that it can be rapidly carried on.

The invention consists chiefly in an adjustable cylindrical support, upon which the boot-leg is drawn, and in arranging, within said cylinder, straps or rods, that are attached to a treadle, so that they will, when fastened to the boot-straps, and when drawn down by the treadle, turn the boot-leg over the upper edge of the cylinder.

A, in the drawing, represents a platform or table, of suitable size and shape, supported on legs B B, that may, by suitable means, be fastened to the floor.

I prefer to so arrange the platform A, by forming a narrow neck, *a*, on it, that it can be used as a seat for the operator.

Between transverse guides *b b*, that are arranged on the surface of the platform, is arranged a transversely-sliding plate, *c*, which is on a level with another fixed plate, *d*, that is secured to the platform A, as shown.

By means of a screw, *e*, which passes through the plate *d* into the sliding plate *c*, can the latter be moved nearer to or further away from the plate *d*, the screw having a crank-handle, *f*, by means of which it can be conveniently turned.

Between the plates *c d* is, by having a recess be-

tween them, formed an aperture, which extends clear through the body of the platform.

Upon the plates *c d* are secured vertical semi-cylindrical plates *C D*, respectively, that face each other with their hollow sides, so as to form an open cylinder, which can be enlarged by moving the slide *c* further away from *d*, and contracted by moving *c* nearer to *d*, by means of the screw.

The upper ends of the plates *C D* are turned over, to form channels for a spring-wire, *g*, which retains the upper part of the cylinder in the requisite circular form.

E represents a treadle pivoted to one of the supports *B*, and drawn up by a spring, *h*.

To it are fastened two rods, *i i*, with hooks, *j j*, at their upper ends.

The boot-leg is placed over the cylinder when sewed, the half, *C*, of the cylinder being laterally adjusted to the size of the boot-leg. The hooks *j* are then fitted through the boot-straps, which are at the upper end of the boot-leg, projecting above the ring *g*. By then pressing upon the treadle, the boot-leg will be turned into the inside of the cylinder, and is then ready for the last.

During the operation, the attendant may apply his hands to the counter, to help the upward motion of the same.

On this machine, from fifty to sixty boot-legs can be turned in one hour.

Having thus described my invention,

What I claim as new, and desire to secure by Letters Patent, is—

1. The wire *g*, arranged in the upper ends of the semi-cylindrical plates *C D*, substantially as herein shown and described, for the purpose specified.

2. The slide *c*, operated by the screw *e*, and carrying the adjustable semi-cylinder *C*, substantially as herein shown and described, to operate as specified.

CORNELIOUS COLLINS.

Witnesses:

ELI BURKET,
JOHN B. HARRIS.
